UNITED STATES PATENT OFFICE.

EDWARD C. WOOD, OF SOMERVILLE, MASSACHUSETTS, ASSIGNOR TO SUBMARINE SIGNAL COMPANY, OF WATERVILLE, MAINE, A CORPORATION OF MAINE.

MOORING FOR BUOYS.

1,115,363.

Specification of Letters Patent.

Patented Oct. 27, 1914.

Application filed November 16, 1910. Serial No. 592,599.

To all whom it may concern:

Be it known that I, EDWARD C. WOOD, of Somerville, in the county of Middlesex and State of Massachusetts, a citizen of the 5 United States, have invented a new and useful Improvement in Moorings for Buoys, of which the following is a specification.

My invention relates especially to buoys containing electrical apparatus for the purpose of signaling either by showing a light, sounding a signal, or otherwise, and is shown in the present case as embodied in a submerged signal bell, the mechanism of which is electrically actuated. 10 When the level of an electrical signaling apparatus attached to a buoy moored in the ordinary way is constantly changing by reason of the waves, the tide, or current, some difficulty has been experienced in maintaining a durable electrical connection between it and the source of electricity because the cable carrying the conductor, however thoroughly it is protected, sooner or later is chafed as the buoy changes its position, 15 either against one of the chains which moors the buoy or against the bottom of the ocean or the river in which the buoy is moored so that the line is short circuited. This chafing is also liable to occur where the signaling apparatus is mounted in the ordinary manner on a tripod which stands on the bottom although in this case the liability is much less, but the mounting of the signaling apparatus on a tripod is not satisfactory owing 20 to the irregularities of the bottom on which the tripod is to stand and its liability to be overthrown under certain circumstances. 25

My invention therefore comprises a buoy for supporting an electrically operating apparatus which buoy is moored by a plurality of cables each attached at one end to a suitable anchorage, one of these cables carrying the incoming and return conductors which form part of it and being protected 30 and strengthened by suitable armor. In this case the conductor cable is kept taut by the buoy and has suitable means connecting it to the buoy, the anchorage, and the feeding conductor so that when set the cable while 35 taut will adjust itself to the conditions of its use. So far as I know an electric cable has never formed one of the moorings of a buoy, and the elements which enter into its use under these circumstances are all new, 40

55 My invention will be understood by refer-

ence to the drawings in which one embodiment thereof is shown.

Figure 1 is a side elevation of a submerged buoy moored in the manner above referred to. Fig. 2 is a top view of the junction box by which the conductor is connected to the feeding conductor. Fig. 3 is a similar view partly in horizontal section and partly in plan. Fig. 4 is a side elevation, and Fig. 5 is a vertical section of the same 60 box. Fig. 6 shows in vertical section the preferred form of anchorage, together with the connection of the junction box therewith, Fig. 7 being a plan of the apparatus shown in Fig. 6. Fig. 8 is a detail of the 65 joint as will be explained below. Fig. 9 shows a means for attaching the cable to the buoy. Fig. 10 is a detail showing the construction of the preferred form of cable, and Fig. 11 shows a modification of the anchorage. 70

My invention in these drawings is shown applied to a submarine signaling bell which is operated by electricity. Such bells are well known in the art and their construction need not be specifically described. They are supported some distance below the surface of the water in order that the tone may have proper carrying possibilities. 75

In the present case A is a buoy of ordinary construction from which is suspended the casing B containing the electric mechanism for ringing the bell, and below that the bell itself B¹. The buoy is provided with a stem A¹ extending through its top 80 and provided with hooks A² by which it may be grappled and hoisted should occasion arise and also with an eye A³ by which it may be lowered when being set. The buoy is moored at some distance below the 85 surface of the water by a chain cable C attached at its lower end to a suitable anchorage C in any usual way and also by the cable D which is of special construction containing within it the wires d which form 90 the conductors connecting the electrical mechanism within the casing B with the shore station (not shown) from which electricity is supplied to ring the bell. Each conductor is insulated and the conductors together are also surrounded with insulating material d¹ of sufficient thickness and of 95 such character as not to be acted upon and disintegrated by water and around this insulating coating I prefer to wind two layers, 100

105

110

each comprising a number of wires d^2 , one layer being given a right-hand wind and the other a left-hand, these layers forming an armor to protect the insulation and the conductor generally and add to the strength of the cable. Such an armored conductor is not in itself new.

The anchorage in its preferred form (see Figs. 6 and 7) comprises a block E of stone or the like of sufficient weight for the purpose and to it is bolted by the bolt e an anchor frame F. This frame as shown is made of a single casting of cast iron and comprises a bottom plate f having an opening through which the bolt e passes. A top plate f^1 is connected to the bottom plate by two uprights f^2 each of which is perforated as at f^3 to allow the cable D to pass through it. The plates f, f^1 are perforated at each end to receive the trunnions g of the rings G, G¹, so that each ring can turn on a vertical axis. The rings are alike, being constructed as in Fig. 8 where the ring G is shown, and are provided with other trunnions g^1 which form a horizontal axis for the part connected to each ring. The ring G at one end of the anchor frame carries by means of its trunnions g^1 a clamp box H and the ring G¹ at the other end of the anchor frame carries by its trunnions g^1 the junction box J.

The clamp box H comprises two plates h, h^1 , and a cylindrical casing h^2 , the whole being bolted together by bolts h^3 . From the plate h^1 projects two arms h^4 , the further ends of which are perforated to receive the trunnions g^1 of the ring G. Thus this clamp box has a movement in a vertical plane because it is carried by the trunnions g^1 and it has a movement in a horizontal plane because the ring G is supported by the trunnions g . The cable is attached to the clamp box H in the following manner: The plate h has an opening through it to receive the cable D and it is also provided with a throat extending inwardly having an enlarged portion h^5 at its inner extremity around which the armor portion of the cable is bent, the armor portion of the cable being cut and its end rolled back around the enlargement h^5 and hammered into place against the smaller portion of the throat and secured with wire at its ends. The casing h^2 is then forced over it, the plate h^1 adjusted and the whole clamped together by the bolts h^3 . The upper end of the cable D is attached to the buoy A in a similar manner (see Fig. 9), the clamp box H¹ being identical in general character with that shown in Figs. 7 and 8, and being similarly connected to a ring G² like the ring G by trunnions g^1 . A⁴ is a yoke piece bolted to the buoy. The arms of this yoke piece are perforated to receive the trunnions g of the ring G². Thus these two clamp boxes H, H¹ are connected, the

one to the buoy and the other to the anchorage by a double or universal joint. The yoke piece A⁴ has a passage a through it for the cable which is attached to the clamp box H¹ in the same way as it is attached to the clamp box H and stripped of its armor is led to the casing B containing the electrical mechanism. Its armor being removed it is rendered flexible for making the necessary connection.

As stated above, the anchor frame shown in Figs. 7 and 8 is perforated at its farther end to receive the trunnions g of the ring G¹ and to the trunnions g^1 of the ring G¹ is attached by arms J¹ the junction box J. The junction box (see Figs. 2 to 5) has a cover J² which is bolted to it, a gasket being used to make a tight joint. The cable D from which the armor has been stripped is led into it and spliced as at d^3 in any suitable way. The box is thereafter filled with some insulating material such as ozite as indicated at j , the gasket and cover are then applied and sealed by a coating of ozite as shown at j^1 , thus making the whole watertight. Thus it serves to protect the splice and with the anchor frame to guide and protect the cable between the clamp boxes. At each end of the junction box is provided a stuffing box j^2, j^3 , through which the cable enters or leaves the junction box as the case may be, and at its outer end the junction box is provided with a clamp box H² to which the cable is secured as above described in connection with the clamp box H. The two ends of the junction box are preferably provided with stuffing boxes. For this purpose one end of the junction box is provided with a threaded opening j^2 . The arms J¹ above referred to form a yoke spreading from a plug j^3 which is threaded and screws into the opening j^2 . The plug j^3 is recessed and the closed end of the recess is perforated as at j^4 to allow the passage of the unarmored cable through it. Within the recess and around the wires is placed a perforated compressible washer j^5 and a perforated follower j^6 having ears j^7 with holes to receive screws j^8 which screw into holes in the plug j^3 . When these screws are screwed up as far as possible the washer j^5 will be compressed by the follower and leakage at that end of the junction box will be prevented. At the other end of the junction box there is a recess j^9 provided, which is perforated at its closed end for the outgoing conductors. A perforated compressible washer j^5 is also provided as before and a perforated follower j^{81} forming part of the plate h^{11} sets into the recesses and is clamped against the washer j^5 by means of screws j^{81} which pass through the plates of the clamp frame H² and into bosses j^{11} on the junction box. The stuffing boxes may be alike if thought best. It will be seen

from this description that the main strain on the cable D is taken up by the armor d^2 by means of which the cable is connected by the two clamp boxes, at one end of the 5 buoy at the other end to the anchorage, and that the armor being removed between the clamp box H and clamp box H^2 , the cable is rendered flexible for passage through the anchor frame to the junction box and for 10 splicing with the feed cable D¹. The cable is thus held so securely and is so protected that there is no danger of chafing of the insulating material on the conductor at the only position where it is unprotected. By 15 removing the armor from so much of the cable as passes through the anchor frame it is rendered flexible so that it may adjust itself as occasion requires, the anchor frame and junction box serving to protect it from 20 abrasion.

In Fig. 11 I have shown another form of anchor frame K, useful under some circumstances, which is bolted to the anchorage E as before and has an angular face k with a threaded opening to receive the end of 25 a section of pipe k¹ which serves to protect the conductor as it passes from the clamp frame to the anchor frame. The clamp box in this case lettered H³ is similar to the 30 clamp box H. The ring G³ in this case is connected by its trunnions g to the arms H⁴ of the clamp box H³ and by its trunnions g¹ to a yoke piece having arms H⁵ and a socket H⁶ into which screws the outer 35 end of the pipe k¹.

The above are given as convenient embodiments of my invention, simple to construct and effective in operation. For ordinary uses I prefer the form shown in Fig. 40 1, but the anchorage shown in Fig. 11 allows a slight play of the cable, the pipe holding it off bottom.

For convenience of expression the joint provided by the ring G may be termed a 45 "universal joint" though technically it is not such, and it is evident that this form of joint is but one of a number of well known joints which may be used for the purpose.

I have stated above that my invention relates especially to buoys containing electrical apparatus for the purpose of signaling, but it is equally applicable to any case where a body containing apparatus to be energized by electric current supplied from a shore 55 station is moored. Such for example would be a mine capable of being exploded by electricity. In using the term "buoy" therefore I do not mean to limit myself to the device ordinarily so-called, but to include any device 60 which will either support an electric apparatus or contain such apparatus for whatever purpose it may be energized.

What I claim as my invention is:

1. A submerged buoy having a plurality 65 of mooring cables, one of which comprises

electric conductors, and means for connecting the cable carrying said conductors to said buoy comprising a clamp box attached to said buoy and having means adapted to clamp said conductor-carrying cable therein 70 whereby said conductor-carrying cable will be prevented from endwise movement in either direction, and jointed means connecting said clamp box with said buoy.

2. A submerged buoy having a plurality 75 of mooring cables, one of which comprises electric conductors, an anchorage and jointed means comprising a clamp box pivotally connected to said buoy and containing means adapted to restrain the conductor-carrying 80 cable from endwise movement in either direction for connecting the cable carrying said conductors with said anchorage.

3. A submerged buoy having a plurality 85 of mooring cables, one of which comprises electric conductors, and means for connecting said conductors to said buoy comprising a universal joint, one member of which is attached to said buoy, and a clamp box comprising means adapted to restrain the conductor-carrying 90 cable from endwise movement.

4. A submerged buoy having a plurality 95 of mooring cables, one of which comprises electric conductors, in combination with an anchorage, two clamp boxes each adapted to receive said conductor-carrying cable and restrain it from endwise movement, and two universal joints one connecting one of said clamp boxes with said buoy and the other 100 connecting the other clamp box with said anchorage.

5. A submerged buoy having a plurality 105 of mooring cables, one of which comprises electric conductors, in combination with an anchorage, and means for connecting said conductors to said anchorage comprising a universal joint and means for restraining 110 said conductor-carrying cable from endwise movement in either direction.

6. A submerged buoy having a plurality 115 of mooring cables, one of which comprises electric conductors, in combination with an anchorage, and means whereby said cable is flexibly connected with said buoy and said 120 anchorage and prevent it from endwise movement in either direction.

7. A submerged buoy having a plurality 125 of mooring cables, one of which comprises electric conductors, an anchorage connected to said cable comprising said conductors and means for relieving the conductors of the mooring strain comprising clamp boxes, one connected to said buoy and the other to said anchorage, and an armor on said last-named cable connected at each end to one of said clamp boxes.

8. A submerged buoy having a plurality 130 of mooring cables, one of which comprises electric conductors, in combination with an

- anchorage and means for securing said electric conductors to said anchorage comprising an anchor frame attached to said anchorage, a clamp box pivotally attached thereto at one end thereof, and a junction box attached to the other end thereof, said conductors being attached to said clamp box and passing through said anchor frame and into said junction box.
- 5 10. 9. As a means for anchoring an electric cable, an anchorage, an anchor block connected thereto, said anchor block being provided with means for supporting said cable, a clamp box, a universal joint connecting said clamp box with said anchor block and means for connecting said cable with said clamp box and preventing it from endwise movement.
- 10 15. 10. A submerged buoy having a plurality of mooring cables, one of said cables comprising insulated electrical conductors having a metallic protecting exterior and means for anchoring one end of said electrical-containing cable to said buoy comprising a universal joint, and means for securing the other end of said cable to a suitable mooring point comprising a universal joint, whereby the movement of said buoy will be allowed for by said universal joints.
- 20 25. 11. As a means for anchoring one end of a cable containing electric conductors, an anchorage, means pivotally connected therewith whereby said cable is prevented from longitudinal movement with reference to said anchorage, said anchorage carrying means to guide and protect said cable.
- 30 35. 12. In combination, a buoy or the like, and means for mooring it comprising an anchorage and a cable consisting of electric conductors and a protecting wire armor, means for connecting said armor with said buoy and also with said anchorage, said means in each case comprising a hinged connection.
- 40 13. In combination, a buoy or the like, and means for mooring it comprising an anchorage, and a cable consisting of electric conductors and a protecting wire armor, means for connecting said armor with said buoy and also with said anchorage, said cable being denuded of its armor at such connections, and said anchorage having means for protecting said denuded cable.
- 45 14. In a buoy mooring and anchorage, a junction box flexibly connected therewith and two cables each comprising insulated electrical conductors and a metallic armor forming the outer surface of said cable, one of said cables extending from said anchorage to a buoy to form a mooring therefor, means comprising a pivotal connection to connect said cable to said anchorage and the other cable extending outwardly from said junction box, the conductors of said cables being electrically connected within said junction box, whereby said buoy may be removed and replaced without disturbing said anchorage, in combination with said buoy.
- 50 55 60 65
